UNITED STATES PATENT OFFICE.

BERNARD R. ANDREWS, OF BRAINTREE, MASSACHUSETTS.

APPARATUS FOR DRYING MATERIAL IN THE FORM OF WEBS.

1,287,172.

Specification of Letters Patent. Patented Dec. 10, 1918.

Application filed April 25, 1918. Serial No. 230,646.

To all whom it may concern:

Be it known that I, BERNARD R. ANDREWS, a citizen of the United States, residing at Braintree, county of Norfolk, State of Massachusetts, have invented an Improvement in Apparatus for Drying Material in the Form of Webs, of which the following description, in connection with the accompanying drawing, is a specification, like characters on the drawing representing like parts.

This invention relates to driers of that type which are designed for drying material in the form of a web and which comprise a plurality of traveling poles over which the web of material is festooned while it is being dried. Drying apparatus of this sort is usually provided with means for delivering the web of material onto the poles successively, the rate of delivery being such relative to the speed of travel of the poles that the material will be festooned over each pole. Such apparatus is also sometimes provided with a clamping roll which engages each pole as the material is being laid thereover so as to clamp the material to the pole and to prevent the weight of the last-formed festoon from causing the material to slip on the pole while a new festoon is being formed.

While the clamping roll can be successfully used on uncoated web material, yet it is not feasible to use it on freshly-coated web material because the engagement of the clamping roll with the freshly-coated surface of the web would injure such surface and thereby result in the production of imperfect goods.

One of the objects of my present invention is to provide a novel means for clamping or holding the web to each pole as it is being festooned thereover, which means operates to perform its function without causing a clamping member to have physical contact with the web. My improved means can be successfully used in connection with freshly-coated web material because since the device does not involve a clamping member that has physical contact with the web there is nothing that can mar or disturb the freshly-coated surface of the web.

Another object of the present invention is to provide novel means for guiding the web as it is delivered to the drying appara-

tus, which means will perform its function without injuring or marring the freshly-coated surface of the web material. In my invention the web is guided as it is delivered to the poles by means of two air jets which are directed against opposite sides of the web, the pressure of the air in the two jets operating to hold the web in proper position as it is delivered to the poles. The web is held to each pole as it is laid thereover by air pressure, this result being herein attained by a device adapted to deliver a jet or sheet of air under pressure against the web as it is laid over each pole. The construction of the guiding means for the web is such that it also assists in holding the web to the pole, for the air current which is delivered against one side of the web is directed into the festoon as the latter is being formed and the pressure of the air against the forming festoon tends to counterbalance the weight of the previously-formed festoon and thus assists in holding the web on the pole.

In order to give an understanding of my invention I have illustrated in the drawings a selected embodiment thereof which will now be described, after which the novel features thereof will be pointed out in the appended claims.

Figure 1 is a vertical sectional view through an apparatus embodying my invention;

Fig. 2 is a section on the line 2—2, Fig. 1;

Fig. 3 is a section through the suction roll;

Fig. 4 shows the operation of the web-guiding and delivering device;

Fig. 5 is a perspective view of the web-guiding device.

The web which is to be dried is indicated at 1 and during the drying operation it is formed in festoons 3 over a plurality of poles 2 as usual in web-drying apparatus. The poles 2 are arranged to travel from one end to the other of the drier, and for this purpose are connected by chains or other flexible connections 4 which passes around the direction pulleys 5, one or more of said pulleys being positively driven to give the requisite movement to the poles. The web is led into the drier at one end over a suitable feed roll 6 and is taken from the drier at the opposite end by any suitable means, such as two delivery rolls 7.

The parts thus far described are or may be all as usual in web-drying apparatus and form no part of my present invention.

In the operation of driers of this type the poles 2 in the upper run of the endless chain are given a traveling movement from one to the other end of the drier, and as each pole passes under the feed roll 6 a festoon 3 of the web is laid thereover, the web hanging 10 in festoons as it passes through the drier until it is taken from the drier by the delivery rolls 7.

In order to insure the proper formation of each festoon it is necessary that the web 15 should be properly guided as it is being laid over each pole and it is also necessary to provide means for preventing the weight of the previously-formed festoon from causing the web to slip on the pole during the initial 20 formative stage of the festoon. As stated above, this invention has for its objects to provide novel means for thus guiding the web and for holding it to the pole during the formation of each festoon.

25 For guiding the web as it is delivered to the pole I provide pneumatic means arranged to deliver an air jet against each side of the web adjacent to the path of movement of the poles, said air jets being delivered 30 downwardly against the web in an inclined direction and operating to hold the web in proper position. Any suitable means may be employed for thus delivering the air jets to the web. I have herein shown for this 35 purpose two nozzle devices 8 and 9, each of which is provided at its lower end with a delivery opening in the form of a slit or a plurality of jet nozzles so situated that when air is delivered therefrom it will assume a 40 sheet-like form which is directed downwardly in an inclined direction against the web. The two delivery openings are indicated at 10 and 11, respectively. The sheet-like air currents which are delivered from 45 the openings 10 and 11 act against both sides of the web and serve to float the web between the nozzles and thus hold it in proper position. With this arrangement the web will be guided between the two nozzles 50 without having anything come in contact therewith at this point which would mar or injure the surface thereof even though it is freshly coated.

For directing the air current or jet against 55 the web as it is laid over each pole, I have provided the nozzle 8 with a branch 12 which is formed with a slit 13 at its lower edge situated directly above the pole over which the web is being festooned. A sheet 60 of air under pressure will thus be delivered through the slit 13 of the nozzle 12, which sheet of air will impinge against the web that contacts with the pole and thus hold the web against the pole with sufficient pressure 65 to prevent it from slipping. This clamping

action of the sheet of air is augmented by the action of the guiding sheet of air which issues from the nozzle 8 for each sheet of air will be directed into each festoon as it is being formed, and the pressure of the air 70 against the forming festoon will tend to counterbalance the weight of the previously-formed festoon.

Fig. 1 illustrates at 3^b a festoon in the initial formative stage which is being 75 formed over the pole 2^a, 3^a indicating the last-formed festoon. The sheet-like current of air which is delivered from the nozzle 8 into the forming festoon 3^b tends to counterbalance the weight of the previously-formed 80 festoon 3^a and this counterbalancing action together with the pressure of the air delivered from the nozzle 12 will prevent the web from slipping on the pole 2^a and will thus insure that the festoons are all formed 85 of the proper length.

Any suitable means may be employed for delivering air to the nozzles 8, 9 and 12. As herein shown said nozzles are connected to a fan 14 by a suitable pipe 15 so that the 90 fan will force air into both nozzles. I will preferably make the nozzles capable of a vibrating movement in the direction of the movement of the poles 2, and this is herein provided for by connecting said nozzles at 95 their ends by yoke members 16 which are provided with trunnions 22 that are pivoted in a suitable bracket 17 carried by the frame 18. These yokes and trunnions are hollow and the pipe 15 leads into one or both of the 100 trunnions and thus a communication is formed between the nozzles and the fan or blower 14. The nozzle 9 is shown as having a finger 18 depending therefrom which is engaged by each pole 2 just before the web 105 is festooned thereover. The engagement of each pole with the finger will cause the nozzles to move with the poles as the festoon is being formed so that during the forming of each festoon the nozzles and poles are moving together. This insures that the air blast from the slit 11 will always be directed against the pole 2 and also insures the proper guiding of the web as each festoon is formed. By the time each festoon has been completely formed the finger 18 will wipe over the pole with which it has been in engagement and the nozzles will be returned to their normal position by means of a 110 spring 19.

If desired a device in the nature of a dashpot 20 may be used for controlling the rearward movement of the nozzles. The feed roll as herein illustrated is in the nature of a suction roll. It is made hollow, as shown 115 in Fig. 3, and is provided with apertures in its periphery. The interior thereof is connected to the intake of the fan 14 by pipes or connections 23 so that the operation of the fan not only sucks the air from within the 120 125

fan to prevent it from slipping. This clamping

roll 6, but also forces the air through the nozzles 8, 9 and 12. The roll is shown as partially surrounded by a shield 21 which covers all of the roll except that part with which the web has contact. The exhaustion of the air from the feed roll will hold the web to said roll by suction and thus the feed roll will operate to positively feed the web as required to deliver it properly to the drying apparatus.

In the device as thus described it will be seen that there is nothing except the air blast which comes in contact with the upper or coated side of the web and that the web will be properly guided as it is fed to the apparatus and will be properly clamped or held to each pole as it is being festooned therewith without having any element coming in contact therewith which would injure or mar the coated surface.

I claim:

1. In a drier, the combination with a plurality of traveling poles over which web material to be dried may be festooned, of means to deliver the web material to said poles successively, and pneumatic means for holding the web on each pole as it is being festooned therewith.

2. In a drier, the combination with a plurality of traveling poles over which web material to be dried may be festooned, of means to deliver the web material to said poles successively, and means to direct a current of air against the web as it is being laid over each pole.

3. In a drier, the combination with a plurality of traveling poles over which web material to be dried may be festooned, of means to deliver the web material to said poles successively, and means to direct a sheet of air into each festoon as it is being formed.

4. In a drier, the combination with a plurality of traveling poles over which web material to be dried may be festooned, of means to deliver the web material to said poles successively, and means acting on each festoon

as it is being formed between two poles to counterbalance the weight of the last-formed festoon.

5. In a drier, the combination with a plurality of traveling poles over which web material to be dried may be festooned, of means to deliver the web material to said poles successively, and means to apply to each festoon as it is being formed a counterbalancing air pressure to counterbalance the weight of the previously-formed festoon.

6. In a drier, the combination with a plurality of traveling poles over which web material to be dried may be festooned, of means to deliver the web material to said poles successively, and pneumatic means for guiding the web material as it is laid over each pole and formed into festoons.

7. In a drier, the combination with a plurality of traveling poles over which web material to be dried may be festooned, of means to deliver the web material to said poles successively, and pneumatic means situated between the web-delivering means and the poles for guiding the web material as it is being laid over each pole and formed into festoons.

8. In a drier, the combination with a plurality of traveling poles over which web material to be dried may be festooned, of means to deliver the web material to said poles successively, and means to direct a current of air against each side of the web between the poles and the delivering means.

9. In a drier, the combination with a plurality of traveling poles over which web material to be dried may be festooned, of means to deliver the web material to said poles successively, and means acting on the portion of each forming festoon between two poles to counterbalance the weight of the last-formed festoon.

In testimony whereof, I have signed my name to this specification.

BERNARD R. ANDREWS.
